UNITED STATES PATENT OFFICE.

RICHARD KITSON, OF LOWELL, MASSACHUSETTS, ASSIGNOR TO THE
KITSON MACHINE COMPANY, OF SAME PLACE.

MACHINE FOR OPENING AND PREPARING COTTON.

SPECIFICATION forming part of Letters Patent No. 374,899, dated December 13, 1887,

Application filed April 25, 1884. Serial No. 129,259. (No model.)

To all whom it may concern:

Be it known that I, RICHARD KITSON, of Lowell, in the county of Middlesex and State of Massachusetts, have invented certain new and useful Improvements in Machines for Opening and Preparing Cotton, of which the following is a specification.

My improvement relates to machines for opening and preparing cotton and other fibrous substances; and it consists in a new arrangement and combination of parts of such machines whereby economy of construction and arrangement is secured and greater ease of operating the same, substantially as hereinafter described and claimed.

In the drawings, Figure 1 is a longitudinal vertical section through a lapper-machine, showing my improvement connected therewith. Fig. 2 is a transverse section through line *x x* of Fig. 1. Fig. 3 is a view of the dust-boxes and fan and its casing detached. Fig. 4 represents a cross-section of the dust-pipe with one member having the door open and another with the door closed. Fig. 5 is a sectional view of a portion of the machine provided with a modification of my improvement. Fig. 6 is a transverse vertical section of the same on a line through the axes of the first pair of screen-cylinders. Fig. 7 is a top view of the dust-pipe and fan detached.

a is the casing of the machine. *a'* is the feed-apron. *a' a'* are the feed-rolls. *B B* are the beaters. *C C* are the condensing-screens. *c c* are the doffer and lap rolls. *b b b* are the laps in position upon the feed-apron to be doubled and fed into the machine. All of these parts of the machine are of ordinary construction and well known.

d d are the air and dust passages, leading from the condensing-screen cylinders *C C* downward in the usual manner. Heretofore the said passages have led directly into a fan or blower placed with its axis parallel to those of the screen-cylinders within the casing of the machine directly underneath the screen-cylinders and near the floor, one such fan or blower being used for each pair of screen-cylinders, and any dust or dirt collecting in the air-passages near the fan was difficult to get cleaned out from its inaccessible location, and, the num-

ber of fans being equal to the number of beaters used in the machine, a large number of working parts were required to support them properly and connect them with the driving-gearings. The wear of so many running parts has also been a considerable expense. To overcome this difficulty, I have combined two pairs of screen cylinders with a single fan so located that the dust-passages where the dust accumulates can be easily cleaned out, and the fan itself is easily accessible and can be made large enough to perform the work required.

F is the floor of the room, upon which the machine stands.

Directly underneath each vertical passage *d* leading downward from the screen-cylinders *I* make a hole through the floor and continue the passage downward into a horizontal dust box or passage, *D*, attached to the under side of the floor in the compartment below *F* that in which the machine is placed. There are two of these dust and air passages *D*, running parallel to each other and directly under the vertical passages *d* at each end of the screen-cylinders, as shown. The lower side of *D* is formed of hinged doors *d'*, which can be dropped down to allow the dust which may collect in them to escape, and then closed again.

Each of the passages *D* has at its end underneath the feed-apron of the machine a part, *d'*, which curves upward and inward, passing through holes in the floor and into each side of a fan or blower, *E*, placed upon the floor underneath the feed-apron, which blower has a discharge-pipe, *E'*, leading downward again through the floor. By this construction of the parts I am enabled to dispense with a separate fan for each pair of revolving screens, as heretofore used, and my fan or blower is placed in a position where it is easily accessible, and can be repaired or cleaned without difficulty. The blower *E* is provided with pulleys *e' e'* on each end of its shaft, by which it may be driven from any suitable counter-shaft. It is of ordinary construction, receiving its air from the passages *D D* at the center and discharging it at the circumference, and need not be further described.

Instead of a pair of screen-cylinders C C following or in the rear of each beater in the machine, a single screen-cylinder may be used, following or in the rear of each beater in the 5 ordinary and well-known manner, without departing from the spirit of my invention.

In order to control the amount of air-draft from each pair of screen-cylinders C C, I place a damper, d^5 , in each of the vertical passages d below the screens, which damper is hung upon a shaft, d^3 , extending transversely of the machine and having its shaft projected out on one side and provided with a crank, d^4 . By turning this crank the passages d may be 15 closed to any desired extent, thus regulating the amount of suction or exhaust from the screen-cylinders above it.

Instead of having two air-passages d from each set of condensing-screen cylinders, only 20 one may be used by closing one of the dampers d^5 entirely to each set of screens.

In Figs. 5, 6, and 7 is shown a modification of my invention, by which one of the 25 dust-pipes D is dispensed with and the vertical passages d lead by means of a Y-shaped passage beneath the lower screen into a single vertical passage and the dust-passages D d^2 , as before described. The damper d^5 is shown as placed below where the passages d unite, 30 with its shaft longitudinally of the machine. The part of the dust-passage d^2 rises to the fan, as before; but to accommodate the single passage the fan is made of the ordinary double-float pattern, and each set of floats on each 35 side of the upper end of the dust-passage d^2 takes its dust from the passage at the center and delivers it through a passage, e , leading down through the floor.

e^3 e^4 represent the outer casings of the two 40 sets of floats, which are mounted on and driven by one shaft and the pulleys e' e' , as before.

What I claim as new and of my invention is—

1. In a machine for opening fibers, the combination of two sets of condensing-screen cylinders, C, having the beater B between them, 45 dust-pipes d , leading from the interior of said

cylinders into a single dust-pipe, and a single fan or blower, E, connected to the latter and adapted to produce a current of air through 50 it and said pipes from the interior of said screen-cylinders, substantially as described.

2. In a machine for opening fibers, the combination of two sets of condensing-screen cylinders, C, having the beater B between them, 55 dust-pipes d , provided with dampers d^5 d^5 and leading from the interior of said cylinders into a common dust-pipe, and a single fan or blower, E, connected to the latter and adapted to produce a current of air through it and said 60 pipes d from the interior of said screen-cylinders, substantially as described.

3. In a machine for opening fibers, the combination of one or more sets of condensing-screen cylinders, C, dust-pipes d , leading 65 from the interior of said cylinders at both ends thereof into a single dust-pipe, the latter extending horizontally beneath the frame of the machine, dampers d^5 d^5 , located in said pipes d , and a single fan or blower, E, connected to said single dust-pipe and adapted 70 to produce a current of air through it and said pipes d from the interior of said screen-cylinders, substantially as described.

4. In a machine for opening fibers, the combination of two sets of condensing-screen cylinders, C, having the beater B between them, 75 dust-pipes d , leading from the interior of said cylinders into a single dust-pipe extending horizontally beneath the frame of the machine and upward past the end of said frame, 80 and a single fan or blower, E, located opposite said end of the machine-frame, with its axis parallel, or nearly so, with that of said screen-cylinders and beater, and connected to said 85 single dust-pipe, and adapted to produce a current of air through it and pipes d from the interior of said screen-cylinders, substantially as described.

RICHARD KITSON.
